(57) **CLAIM**

The ornamental design for a table, as shown and described.

DESCRIPTION

FIG. 1 is a perspective view of a table.

FIG. 2 is a front elevation view thereof. A rear elevation view, a right side elevation view and a left side elevation view are identical to the front elevation view.

FIG. 3 is a top plan view thereof.

FIG. 4 is a bottom plan view thereof.

FIG. 5 is a sectional view of line 5-5 in FIG. 2.

FIG. 6 is a sectional view of line 6-6 in FIG. 2; and,

FIG. 7 is an enlarged view of the portion 7-7' in FIG. 6.
